CLAMP FOR BARREL PUMPS

Wilbur Jackson, Chatsworth, Ga.

Application January 16, 1947, Serial No. 722,399

1 Claim. (Cl. 285—30)

1

My invention relates to a clamp or locking device which is well adapted for clamping the cylinder of a pump upon a barrel.

An important object of the invention is to provide means, including a barrel hole fitting or screw threaded plug, whereby the cylinder of a pump may be readily clamped in a selected adjusted position, upon any depth of barrel.

A further object of the invention is to provide a pump clamp, for quickly and conveniently locking a pump at any depth in a barrel, without deforming or injuring the cylinder or barrel of the pump.

A still further object of the invention is to provide a clamp or locking device of the above mentioned character, which is extremely simple and quite inexpensive to manufacture.

Other objects and advantages of the invention will be apparent during the course of the following description.

In the accompanying drawings, forming a part of this application, and in which like numerals are employed to designate like parts throughout the same,

Figure 1 is a side elevation of the clamp or locking device embodying my invention, and showing the same in use for clamping a pump cylinder upon a barrel, parts in section.

Figure 2 is an enlarged plan view of the clamp or locking device, parts in section.

Figure 3 is a central vertical section taken on line 3—3 of Figure 2, and,

Figure 4 is a vertical section taken on line 4—4 of Figure 2.

In the drawings, where for the purpose of illustration, is shown a preferred embodiment of my invention, the numeral 5 designates a barrel or liquid filled drum, having one of the standard sizes of screw threaded barrel holes 6 provided in one of its ends. Arranged upon the barrel 5, in position for removing or pumping out the liquid contents thereof, is a lift type or barrel pump 7, including the pump cylinder 8. This pump cylinder 8 extends through a cylindrical opening 9 in a screw threaded barrel hole fitting or plug 10, and is adapted to be clamped in place within this opening 9 by means to be described. The pump cylinder 8 has a close fit within the opening 9, but is free to slide, or to be longitudinally adjusted therein. The barrel hole fitting 10 has a hexagonal head 11, and external screw threaded portions 12 and 13, to fit different sizes of standard barrel holes. The screw threaded portion 12 is shown in engagement within the screw threaded barrel hole 6, Figures 1 and 3.

2

Arranged upon the top of the fitting 10 is a flat preferably generally circular clamp plate or ring 14, having an elongated radial handle 15 formed integral therewith. The clamp plate 14 has a central circular opening 16, for receiving the pump cylinder 8, and this opening may be of the same diameter as the diameter of the opening 9. Formed in the clamp plate 14, and preferably arranged near the handle 15 is a circularly curved slot 17. This circularly curved slot 17 is eccentric with respect to the circular opening 16 and also with respect to the opening 9, see Figure 2. A screw 18, seated upon a washer 19, engages within a screw threaded opening 20 in the barrel hole fitting 10; and this screw passes through the slot 17, which is slightly wider than the diameter of the screw. The eccentric slot 17 is arranged so that when the clamp plate 14 is turned about the pump cylinder 8, until the shank of screw 18 is at the end of the slot 17 radially nearest to the center of the opening 16, the pump barrel 8 will be free to be adjusted longitudinally, as desired.

The operation of the clamp or locking device is as follows:

25 The screw 18 is loosened, so that the clamp plate 14 may be turned about the pump cylinder 8, to loosen or free such cylinder. When the shank of the screw 18 reaches the end of the eccentric slot 17, radially nearest to the center of the circular opening 16, the pump cylinder will be free, and it is then adjusted longitudinally to the desired depth in the barrel 5. When this has been done, the user turns the clamp plate 14 in the opposite direction, for clamping or locking the pump cylinder 8 in the selected adjusted position. The handle 15 is, of course, provided to facilitate the turning of the clamp plate 14. The coaction of the screw 18 within the eccentric slot 17 causes the pump barrel 8 to be securely clamped within the opening 9 of fitting 10. The clamp plate 14 exerts a clamping force upon one side of the pump cylinder, and the pump cylinder is clamped or locked against the opposite side of the opening 9. A wedging action between the stationary screw 18 and the eccentric slot 17 occurs when the clamp plate 14 is turned, for tightening the same. When the pump barrel 8 has thus been clamped in the selected adjusted position, the screw 18 may be tightened to lock the clamp plate in the clamped position.

It is thus seen that an extremely simple device is provided, whereby the pump may be quickly and conveniently adjusted to different depths within a barrel. The clamp or locking device is positive 55 in action, and it is extremely strong and durable.

It is to be understood that the form of my invention herewith shown and described is to be taken as a preferred example of the same, and that various changes in the shape, size, and arrangement of parts may be resorted to, without departing from the spirit of my invention, or the scope of the subjoined claim.

Having thus described my invention, what I claim is:

A fitting adapted to be mounted upon a barrel and provided with a main opening, a clamp plate arranged upon the fitting and provided with a main opening and an eccentric slot, the main openings being adapted to receive the cylinder of a pump or the like, and a pin secured to the fitting and projecting into the eccentric slot and co-act-

ing with the slot when the clamp plate is turned for shifting the clamp plate bodily laterally to clamp the cylinder against the side wall of the main opening in the fitting.
